(57) **CLAIM**

We claim the ornamental design for a hook bracket for mounting articles on a wall, as shown and described.

DESCRIPTION

FIG. 1 is a top, front, left side perspective view of a hook bracket for mounting articles on a wall.

FIG. 2 is a right side elevation view of the hook bracket for mounting articles on a wall, the left side elevation view being a mirror image.

FIG. 3 is a front elevation view of the hook bracket for mounting articles on a wall.

FIG. 4 is a rear elevation view of the hook bracket for mounting articles on a wall.

FIG. 5 is a top plan view of the hook bracket for mounting articles on a wall; and,

FIG. 6 is a bottom plan view of the hook bracket for mounting articles on a wall.

The broken lines in the drawing depict environmental subject matter only and form no part of the claimed design.
